DRAWER PULL SHIELD

Charles R. Wasnewsky, 50 Newton Ave.
Pittsfield, Mass. 01201

Filed Jan. 18, 1968, Ser. No. 10,202

Term of patent 7 years

Int. Cl. D8—03

U.S. Cl. D8—179

Fig.1.

Fig.2.

Fig.3.

Fig.4.

FIGURE 1 is a front view of a drawer pull shield, showing my new design thereof, the rear view being substantially a mirror image thereof;

FIGURE 2 is a side, edge view of the drawer pull shield;

FIGURE 3 is a front view of a modified form of my new design, the rear view being substantially a mirror image thereof; and

FIGURE 4 is a side, edge view of the drawer pull shield shown in FIGURE 3.

I claim:

The ornamental design for a drawer pull shield, as shown and described.
